CLAIM

The ornamental design for a clipboard for a shopping cart push bar, as shown and described.

DESCRIPTION

FIG. 1 is a top, right front perspective view of a clipboard for a shopping cart push bar showing our new design;

FIG. 2 is a front elevational view thereof;

FIG. 3 is a rear elevational view thereof;

FIG. 4 is an end elevational view thereof, the end opposite being a mirror image of the end shown in FIG. 4;

FIG. 5 is a top plan view thereof; and,

FIG. 6 is a bottom plan view thereof.

FIG. 1

FIG. 2

FIG. 3

FIG. 4

FIG. 5

FIG. 6
